Carl M. Sinclair
Atty.

UNITED STATES PATENT OFFICE.

CHARLES C. RIEFSNYDER, OF DES MOINES, IOWA; ROSE A. REIFSNYDER, ADMINISTRATRIX OF SAID CHARLES C. RIEFSNYDER, DECEASED.

DESIGN FOR A TAG.

53,156.

Specification for Design.

Patented Apr. 1, 1919.

Application filed December 30, 1918. Serial No. 268,990. Term of patent 14 years.

To all whom it may concern:

Be it known that I, CHARLES C. RIEFSNYDER, a citizen of the United States of America, and resident of Des Moines, Polk county, Iowa, have invented a new, original, and ornamental Design for Tags, of which the following is a specification, reference being had to the accompanying drawing, forming part thereof.

Copies of this patent may be obtained for five cents each, by addressing the "Commissioner of Patents, Washington, D. C."

Figure 1 is a front elevation, Fig. 2 a rear elevation, Fig. 3 a side elevation and Fig. 4 an end elevation of a tag, showing my new design.

I claim:

The ornamental design for a tag, as shown.

CHARLES C. RIEFSNYDER.

It is hereby certified that in [REDACTED] Letters Patent No. 53,156, granted April 1, 1919, upon the application of Charles C. Riefsnyder, of Des Moines, Iowa, for a design for a Tag, an error appears requiring correction as follows: In the grant and in the heading to the printed specification the name of the administratrix and of the patentee, second occurrence, is erroneously given as "Reifsnyder", whereas said name should be given as *Riefsnyder*; and that the said Letters Patent should be read with this correction therein that the same may conform to the record of the case in the Patent Office.

Signed and sealed this 22d day of April, A. D., 1919.

[SEAL.]

F. W. H. CLAY,
Acting Commissioner of Patents.
